Inventor:

James A. Whalen

UNITED STATES PATENT OFFICE.

JAMES A. WHALEN, OF BROOKLYN, NEW YORK.

IMPROVEMENT IN REVOLVING FIRE-ARMS.

Specification forming part of Letters Patent No. 35,052, dated April 22, 1862.

To all whom it may concern:

Be it known that I, JAMES A. WHALEN, of the city of Brooklyn, in the county of Kings and State of New York, have invented a new and useful Improvement in Revolving Ordnance and Fire-Arms; and I do hereby declare that the following is a full, clear, and exact description of the same, reference being had to the accompanying drawings, forming part of this specification, in which—

Figure 1 is a longitudinal vertical section of a cannon with my improvements. Fig. 2 is a transverse vertical section of the same.

Similar letters of reference indicate corresponding parts in the two figures.

This invention consists in a novel way of securing the many-chambered cylinder of a revolving cannon or small-arm in place, whereby its easy removal and replacement, when under any circumstances desirable, are provided for.

The principal objects of the invention are, first, to provide, by the use of two or more cylinders that may be quickly changed at pleasure, for the rapid repetition of the discharge of revolving ordnance or small-arms without overheating the chambers; second, to provide for the loading of a piece of ordnance, arranged on the deck of a ship or other vessel or in barbette, by men below the deck or water-line, or below the embrasure through which the gun is fired.

To enable others to make and use my invention, I will proceed to describe its construction and operation.

A is the barrel, rigidly secured to a strong horizontal frame, B, within which the many-chambered cylinder C is arranged to rotate about its axis. The cylinder C has its axis arranged parallel with the bore of the barrel and its chambers *a a* parallel with its axis, as in most revolvers. It is bored centrally throughout for the reception of the axis-pins *b* and *c*, and counterbored from the rear for the reception of a spiral spring, *d*, which is coiled round the pin *b*; and the counterbore has inserted in its rear a bush, *e*, to which both pins *b* and *c* are fitted, the said bush leaving room enough for the necessary movement of the spring lengthwise of the cylinder. The pin *b* is of a length not greater than that of the cylinder, so that it may be contained within the cylinder without protruding from either end thereof;

and the spring *d* is applied to act against a collar, *b'*, fast on the said pin, for the purpose of pressing the said collar back against the bush *e*, and so withdrawing the pin entirely within the cylinder when the said pin is not otherwise pressed forward, as will be presently described. The other pin, *c*, is arranged to work parallel with the barrel through the back part of the cylinder-frame B, exactly opposite to a hole, *f*, that is provided in the front part of the said frame, to constitute a bearing for the front end of the pin *b*; and the said pin *c* has applied to it within the frame a spring, *g*, which is so much stronger than the one, *d*, applied to the pin *b* that when the cylinder is placed in the frame, with the pin *b* opposite to *c* and *f*, the said pin *b* will be pressed forward into the hole *f*, and the pin *c* will enter the cylinder, and the cylinder will thus be held in place and supported in such a manner as to permit its rotation about its axis, the pin *b* turning with the cylinder and in the bearing *f* and the pin *c* being stationary.

The cylinder, secured and supported as described, can be released from the frame by simply drawing back the pin *c* by power applied to its rear end, which protrudes through the rear of the frame. This drawing back of the pin *c* allows *b* to be forced back by its spring *d*, and thus be withdrawn entirely within the cylinder, which, so far as its axis-pin is considered, is left free to drop out from the frame and permit another cylinder to be inserted thereinto in an upward direction; but the stop *h*, which is employed to arrest the cylinder in its rotation with the chambers opposite to the barrel, requires to be drawn back along with the pin *c*.

The stop *h*, above mentioned, consists of a short round-ended bolt arranged to work in the back of the frame B parallel with the pin *c*, and to enter a series of notches in the rear of the cylinder. This bolt has applied to it a spring, *i*, which throws it forward into the notches of the cylinder, but permits it to be moved back by the pressure against it of the beveled sides of the said notches when power is applied to the cylinder to produce its rotation. The movement of the stop *h* to stop and permit the rotation of the cylinder is independent of the pin *c*; but when the pin is drawn back to release the cylinder it is made

to draw back the stop by its action upon an arm, *j*, attached to the latter. This arm *j* has provided for it in the pin along notch, *k*, which prevents the pin from interfering with the proper action of the stop, the said arm then working freely in the notch *k*. The interior of the back part of the frame *B* is fitted with a steel recoil-plate, *D*, which, being movable on taking out the screws *ll* which secure it in place, provides for the insertion and adjustment of the springs *g* and *i*.

The rotation of the cylinder may be effected by any suitable means. In Fig. 2 it is shown with ratchet-notches *m m* in its periphery, to

be acted upon by a spring-pawl, *n*, attached to a lever, *E*, arranged to work up and down between the cylinder and one side of the frame in a cavity, *p*, provided for it in the frame.

What I claim as my invention, and desire to secure by Letters Patent, is—

The two pins *b c* and their springs *d* and *g*, applied, in combination with each other and with the cylinder and cylinder-frame, substantially as and for the purpose herein specified.

JAMES A. WHALEN.
